(57) **CLAIM**

The ornamental design for a hat with a rear design, as shown and described.

DESCRIPTION

FIG. 1 is a rear perspective view of a first embodiment of a hat with a rear design;

FIG. 2 is a rear elevational view thereof;

FIG. 3 is a front elevational view thereof;

FIG. 4 is a first side elevational view thereof;

FIG. 5 is a second side elevational view thereof;

FIG. 6 is a top plan view thereof;

FIG. 7 is a bottom plan view thereof;

FIG. 8 is a rear perspective view of a second embodiment of a hat with a rear design;

FIG. 9 is a rear elevational view thereof;

FIG. 10 is a front elevational view thereof;

FIG. 11 is a first side elevational view thereof;

FIG. 12 is a second side elevational view thereof;

FIG. 13 is a top plan view thereof; and,

FIG. 14 is a bottom plan view thereof.

The broken lines shown in the figures depict portions of the hat that form no part of the claimed design.

1 Claim, 10 Drawing Sheets
